DIRECTORY ATTACHMENT FOR TELEPHONES

Filed March 26, 1928

FIG. 1.

FIG. 2.

FIG. 4. FIG. 5.

INVENTOR:—

5 LESTER L. SHERWOOD.
BY Martin P. Smith Atty.

UNITED STATES PATENT OFFICE

LESTER L. SHERWOOD, OF LOS ANGELES, CALIFORNIA

DIRECTORY ATTACHMENT FOR TELEPHONES

Application filed March 26, 1928. Serial No. 264,718.

My invention relates to a directory attachment for telephones and has for its principal object, the provision of a relatively simple, practical and convenient attachment, that is adapted to be positioned on the mouthpiece of a telephone transmitter, and which attachment is provided with a card or cards upon which may be written or printed telephone numbers that are frequently used by the telephone subscriber.

Further objects of my invention are, to provide a directory attachment for telephones that is inexpensive of manufacture and which may be advantageously employed as an advertising medium, and further, to provide a device of the character referred to that may be easily and quickly applied to the transmitter of an ordinary telephone, and which device, when properly applied for use in nowise interferes with use of the phone or the service thereof.

With the foregoing and other objects in view, my invention consists in certain novel features of construction and arrangement of parts that will hereinafter be more fully described and claimed and illustrated in the accompanying drawing, in which—

Fig. 1 is a front elevational view of a directory attachment of my improved construction.

Fig. 2 is an elevational view of the mouthpiece portion of a telephone transmitter and showing my improved directory attachment positioned thereon, said attachment being shown in vertical section.

Fig. 3 is an enlarged detail section taken on the line 3—3 of Fig. 1.

Fig. 4 is a front elevational view of a modified form of the directory attachment.

Fig. 5 is a vertical section taken on the line 5—5 of Fig. 4.

Referring by numerals to the accompanying drawings and particularly to the form of device illustrated in Figs. 1, 2 and 3, 10 and 11 designate respectively the front and rear members of the body of the attachment, said members being formed from a single piece of material such as leather, celluloid, fibre or the like, said section of material being bent double to form the front and rear walls, and

formed thru the centers of the two walls or the front and rear members, are aligned circular apertures 12 which accommodate the inner end portion of the mouthpiece of the telephone transmitter when the device is applied thereto.

Seated in the lower corner of the rear wall or member 11 of the body of the device, are the stud members 13 of ordinary snap fasteners and seated in the lower corners of the front wall or member 10, are socket members 14 that are adapted to receive the projecting portions of the studs 13, thereby providing a readily detachable connection between the lower corner of the front and rear walls or members.

Pivottally mounted on the projecting portion of each stud 13, and arranged between the front and rear members 10 and 11, are substantially rectangular sections 16 of cardboard, celluloid, or the like, and the front faces of these members 16 are provided with lines or spaces upon which may be written names and telephone numbers.

The size of the pivoted member 16 is such that when the same are swung upwardly and inwardly, they occupy positions within the side portions of the holder between the front and rear walls 10 and 11, thereof, and the outer or upper edges of said members 16 are curved so that they will readily pass into position between the front and rear walls, beneath the folded or bent portion that connects the upper edges of said front and rear walls.

Formed integral with the outer edge of each member 16, adjacent to the upper edge thereof, is an ear or tab 17 that may be readily engaged to pull the member 16 outwardly and downwardly from its position within the holder, and the intermediate portion of the inner edge of each member 16 is notched or cut away as designated by 18 for the accommodation of the inner portion of the mouthpiece of the telephone when the member 16 is positioned within the holder.

Where the attachment is used for advertising purposes, the advertisement or advertisements of merchants or business houses may be printed on the front face of the front

member 10, and in order to add to the utility of the device, a small calendar may be secured in any suitable manner on the lower portion of the front face of member 10, as illustrated in Fig. 1.

When the attachment is positioned upon the transmitter of a telephone, the mouthpiece is unscrewed from said transmitter and after the small end of said mouthpiece is inserted thru the apertures 12, said mouthpiece is again screwed into position on the transmitter, and thus the attachment is supported upon the inner end of the mouthpiece where it may be readily observed by persons using the telephone.

Where the attachment is made of relatively thin material, it may be clamped in position between the shoulder at the inner end of the threaded portion of the mouthpiece and the front face of the transmitter, or if said attachment is made of heavier material, it may be retained on the inner portion of the mouthpiece by a ring 19 of coiled wire or the like (see Fig. 2).

Where this form of attachment is positioned on the telephone, the subscriber may write in the spaces on the members 16, the telephone numbers frequently used, for instance the home, the office or place of business, the garage, doctor or tradesmen, and when using the phone, it is comparatively an easy matter to engage the ear or tab 17 of the pivoted member 16 and swing the same outwardly and downwardly in order to read the numbers written or printed on the face of said member.

In the modified construction illustrated in Figs. 4 and 5, the attachment comprises a substantially rectangular section 20 of leather, fibre, celluloid or the like, provided in its center with a circular aperture 21 for the accommodation of the inner portion of the telephone mouthpiece, and arranged on the upper portion of the front face of the member 20, is a section 22 of celluloid or analogous transparent material having its side and lower edges secured in any suitable manner, preferably by a row of stitching 23, to the member 20. Formed thru the lower portion of this transparent member 22 is an opening 24 that coincides with the opening 21. Removably positioned in the pocket or space between the transparent member 22 and the member 21, is a card 25, on the face of which may be written or printed the numbers of telephone subscribers frequently called. Projecting upwardly from the center of the inserted card 25 is an ear or tab 26 that serves as a handle when said card is removed or inserted.

The front face of that portion of the member 20 below the lower edge of the transparent member 22 may be utilized for advertising purposes.

Thus, it will be seen that I have provided

a directory attachment that is relatively simple in construction, inexpensive of manufacture, capable of being easily and quickly applied to the mouthpiece of telephones without in any way interfering with the service afforded by the telephone and said device being very effective in performing the functions for which it is intended.

It will be understood that minor changes in the size, form and construction of the various parts of my improved directory attachment for telephones may be made and substituted for those herein shown and described without departing from the spirit of my invention, the scope of which is set forth in the appended claims.

I claim as my invention:

1. A directory attachment for telephones, comprising a holder having front and rear walls, there being coinciding openings formed through the central portions of said walls for the accommodation of the mouth piece of a telephone, means passing through the lower corners of the front and rear walls for detachably connecting the same, data bearing cards arranged between said front and rear walls to the sides of the openings therein, which cards are pivotally mounted on the detachable fastening means and the inner edges of said cards being notched for the accommodation of the mouth piece that passes through the openings in said front and rear walls.

2. A directory attachment for telephones, comprising a holder having front and rear walls, there being coinciding openings formed through the central portions of said walls for the accommodation of the mouth piece of a telephone, means passing through the lower corners of the front and rear walls for detachably connecting the same, data bearing cards arranged between said front and rear walls to the sides of the openings therein, which cards are pivotally mounted on the detachable fastening means, the inner edges of said cards being notched for the accommodation of the mouth piece that passes through the openings in said front and rear walls and tabs projecting outwardly from the upper portions of the side edges of said cards.

In testimony whereof I affix my signature.

LESTER L. SHERWOOD.
